UNITED STATES PATENT OFFICE

2,509,961

REFRIGERATOR CAR FLOOR RACK AND
GUTTER CONSTRUCTION

Edward S. Cisco, Highland, Ind., assignor to
Standard Railway Equipment Manufacturing
Company, Chicago, Ill., a corporation of Delaware

Application September 8, 1945, Serial No. 615,186

7 Claims. (CL. 105—422)

1

This invention relates to improvements in railway refrigerator cars, and more particularly to the floor construction for refrigerator cars of the overhead bunker type, but the invention is utilizable in railway cars of other types.

The conventional refrigerator car floor is of wood with insulation thereunder and may be lined with a metal floor sheet to aid in keeping the wood and insulation dry. A gutter is formed at substantially the juncture of the floor with each side wall, said gutter preferably inclining in opposite directions toward a drain to carry liquid accumulating in the gutter outside of the car. One side wall of the gutter is formed so that it may be conveniently joined to the lower edge of a flue sheet and form a watertight joint. The floor rack for such cars comprises a plurality of preferably transverse stringers extending from side to side of the car, to which are attached a plurality of longitudinally disposed spaced slats extending from end to end of the car and forming the lading supporting floor. Said racks are usually hinged to the car so that they may be raised against the side walls to thereby permit cleaning of the floor, as by flushing with a hose, or otherwise, as preferred. Due to high speed of cars, rough roadbed, etc., it sometimes happens that water collecting in the gutter is thrown toward the interior of the car and it splashes up through the space between the slats to the lading resting thereon, thereby damaging said lading.

The principal object of the invention is to so form the gutter and the edges of the floor rack slats so that any surging of the liquid collecting in the gutter cannot splash therefrom through the rack into the lading compartment.

Other objects and advantages of the invention will appear in the following description thereof.

Referring now to the accompanying drawing forming part of this application and wherein like reference characters indicate like parts.

The figure is a vertical transverse cross section through the adjacent parts of the wall and floor of a railway refrigerator car embodying my invention.

In the drawing the usual parts of a railway refrigerator car are shown, such as the side sill 1; floor rack 2, supported on preferably 2 x 4 stringers 3, to provide a space 4 between said rack and the floor proper, it being understood that the racks are made in sections and of approximately 1 x 4 lumber spaced about $\frac{3}{4}$ " apart for convenience in handling.

The side wall comprises outside sheathing 5; outer posts 6; insulation 7; a plurality of spaced

2

vertically disposed ducts or flues 8; spaced inner posts 9; and inner lining 10 secured to said posts in any acceptable manner. The side wall is thus adapted for use with overhead bunkers, the side wall flues 8 conducting chilled air from a refrigerant compartment adjacent the car roof to the space 4 between the floor and floor rack 2.

The floor of the car comprises a metallic sheet 12; sub-floor 13; insulation material 14 and lower 10 metallic sheet 15. A gutter 17 is formed in the floor of plate material and is located at the juncture of the floor and wall. Said gutter 17 is provided with an outer wall 18 which extends upwardly and inwardly, and the upper edge of which is turned upwardly and outwardly forming a flange 19 which underlaps the lower edge 20 of the sheet forming the flue 8 and is secured thereto, as by welding 21. The inner wall 22 of the gutter 17 is also inclined upwardly and inwardly 20 and provided with a laterally extending flange 23 which underlaps floor sheet 12 and is secured thereto, as by welding 24. Thus both walls of the gutter are substantially parallel and upwardly and inwardly inclined, as clearly shown in the drawing. Gutter 17 also preferably inclines in opposite directions longitudinally toward a drain 25 for conducting moisture from said gutter outside of the car. It is thus evident that if any water in the gutter is thrown therefrom, because of the aforesaid service movements of the car, it would be thrown upwardly and inwardly due to the inclination of the side walls of the gutter.

It will be noted that the adjacent edges of the outer few slats 30 of the rack are trimmed so that they incline about 60° downwardly and inwardly, or in other words, opposite to the inclination of the walls 18 and 22 of the gutter 17. Thus any water from gutter 17 which might possibly be thrown upwardly and inwardly against the lower surface of slats 30 because of surging due to service movements of the car, obviously would not change its course to an upward and outward direction in order to pass through the inclined openings between said slats 30 and, consequently, 45 would be confined to the space 4 and flow downwardly on floor sheet 12 to the gutter and ultimately to drain 25 and outside of the car.

It is necessary to provide a space 31 of approximately 1" in width between the lining 10 and outermost slat 30 to provide room for the rack to pivot on its hinge upwardly against said lining, but the inclination of the walls 18 and 22 of the gutter 17 is also such that surging of liquid in said gutter would be deflected inwardly of said opening 31 and not pass therethrough.

The accompanying drawing illustrates the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car having a wall, a flue associated with said wall, a main floor having a gutter arranged to receive liquid from said flue, and a lading supporting floor spaced above said main floor wherein said gutter is provided with an upwardly and inwardly inclined side and said lading supporting floor having apertures therein for circulation of air therethrough, said apertures being inclined downwardly and inwardly so that water in said gutter surging against said inclined side of the gutter will not splash through said apertures.

2. In a refrigerator car having a wall, a flue associated with said wall, a main floor having a gutter arranged to receive liquid from said flue, and a lading supporting floor spaced above said main floor and spaced from said wall; wherein said gutter is provided with an upwardly and inwardly inclined outer side, the inclination of said gutter wall being such that water in said gutter surging against said inclined side of the gutter will not splash through the space between the load supporting floor and said wall.

3. In a refrigerator car having a main floor having a gutter and a lading supporting floor spaced above said main floor wherein said gutter is provided with an upwardly and inwardly inclined side and said lading supporting floor having apertures therein for circulation of air therethrough, said apertures being inclined downwardly and inwardly so that water in said gutter surging against said inclined side of the gutter will not splash through said apertures.

4. In a refrigerator car having a wall, a main floor having a gutter and a lading supporting floor spaced above said main floor and spaced from said wall; wherein said gutter is provided with

5 an upwardly and inwardly inclined outer side, the inclination of said gutter wall being such that water in said gutter surging against said inclined side of the gutter will be directed away from the space between the lading supporting floor and said wall.

10 6. In a refrigerator car having a wall, a main floor and a lading supporting floor spaced above said main floor wherein said wall adjacent said floor is upwardly and inwardly inclined and said lading supporting floor having apertures therein for circulation of air therethrough, said apertures being inclined downwardly and inwardly so that water on said floor surging against said 15 inclined part of said wall will not splash through said apertures.

7. In a refrigerator car having a wall, a main floor having a gutter and a lading supporting floor spaced above said main floor and wherein said gutter is provided with upwardly and inwardly 20 inclined sides and said lading supporting floor having downwardly and inwardly inclined apertures therein for circulation of air therethrough so that water in said gutter surging against said 25 inclined sides of the gutter will not splash through said apertures.

8. In a refrigerator car having a wall, a main floor and a lading supporting floor spaced above said main floor and spaced from said wall wherein in a portion of said wall adjacent said main floor is upwardly and inwardly inclined, the inclination of said portion being such that water on said floor surging against said inclined portion of said 30 wall will be directed away from the space between the lading supporting floor and the wall.

EDWARD S. CISCO.
